(57) **CLAIM**

The ornamental design for an exercise machine component, as shown and described.

DESCRIPTION

FIG. 1 is a front perspective view of an exercise machine component according to an embodiment of our new design; FIG. 2 is a front elevation view of the exercise machine component of FIG. 1;

FIG. 3 is a rear elevation view of the exercise machine component of FIG. 1;

FIG. 4 is a right side elevation view of the exercise machine component of FIG. 1;

FIG. 5 is a left side elevation view of the exercise machine component of FIG. 1;

FIG. 6 is a top plan view of the exercise machine component of FIG. 1; and,

FIG. 7 is a bottom plan view of the exercise machine component of FIG. 1.

The broken lines show portions of the exercise machine component that form no part of the claimed design. The paired long-short-long dashed lines represent a symbolic break showing bounds of the claimed design and form no part of the claimed design. The area between the paired long-short-long dashed lines forms no part of the claimed design.
